DESIGN FOR A NEWEL-POST.

UNITED STATES PATENT OFFICE.

WILLIAM C. HANNA, JR., OF NEW YORK, N. Y., ASSIGNOR TO J. W. FISKE, OF SAME PLACE.

DESIGN FOR A NEWEL-POST.

SPECIFICATION forming part of Design No. 18,882, dated January 29, 1889.

Application filed September 26, 1888. Serial No. 286,467. Term of patent 7 years.

To all whom it may concern:

Be it known that I, WILLIAM C. HANNA, Jr., of New York, in the county of New York and State of New York, have invented a certain 5 new and useful Design for a Post, of which the following is a specification.

My invention consists of a new design for a post to be used as a newel-post or as a post for railings.

10 The accompanying photograph represents the post in front elevation.

The design consists of a post made in the form or configuration of an owl, A, standing on a hemispherical base, B.

15 In order to render it more ornamental, the wings are represented as projecting slightly

along each side of the body, which stands erect, and their lower ends or tips are represented as curved around to the front and brought together just above the feet, as shown. 20 The breast is also ornamented with a figure, as shown in the accompanying photograph.

What I claim is—

The herein-described design for a post, consisting of the part A, in the form of an owl 25 and the base B, substantially as shown.

In witness whereof I hereunto set my hand in the presence of two witnesses.

WM. C. HANNA, JR.

Witnesses:

L. I. SOUTHARD,
J. W. VANDEWATER.
